UNITED STATES PATENT OFFICE.

JOHN ALEXANDER WHYTE, OF TORONTO, CANADA.

ELECTRIC SIGNALING AND ELECTROPNEUMATIC TRAIN-CONTROL SYSTEM.

No. 806,035.

Specification of Letters Patent.

Patented Nov. 28, 1905.

Application filed September 2, 1904. Serial No. 223,160.

To all whom it may concern:

Be it known that I, JOHN ALEXANDER WHYTE, electrician, a subject of the King of Great Britain, residing in the city of Toronto, 5 in the county of York, in the Province of Ontario, Canada, have invented certain new and useful Improvements in Electric Signaling and Electropneumatic Train-Control Systems, of which the following is a specification.

10 My invention relates to improvements in electric-signaling and electropneumatic train-control systems of the normal clear class; and one object of my invention is to notify the engineer or motorman by electrically-operated means within his cab when a rail or the wiring in his block has been broken, when a switch is open therein, or when a current-conducting obstruction or train is within his block.

15 Another object of my invention is to equip 20 with my blocks a single railroad-track over which traffic moves back and forth, so that all accidents may be averted thereon.

In carrying out my invention I combine it 25 with the block and apparatus described and claimed in my application, Serial No. 196,776, filed March 5, 1904.

The invention consists, essentially, in dividing the track into a series of, for example, east-bound blocks, each block comprising a 30 first third rail divided into insulated sections, in dividing the first track-rail into insulated sections, in utilizing the second track-rail as a common conductor for all the blocks, in suitably wiring the proper insulated sections 35 of the first third rail and said first track-rail to each other and to said second track-rail, in completing the circuit by means of the train, in dividing the track into a series of, for example, west-bound blocks comprising a 40 second third rail divided into insulated sections, in providing line-wires connecting each insulated section of said second third rail to the immediately preceding insulated section of said first track-rail and completing the circuit by means of the train, in providing electrically-operated means within the engineers' 45 cabs whereby they will be notified of the condition of the block they are in, as hereinafter more particularly explained.

50 As will be seen from the drawings, the blocks overlap each other. These drawings illustrate a single track, and the trains are supposed to move, for example, eastward and westward over same. The current is always 55 flowing through the apparatus in the engi-

neer's cab and the block in circuit with same when the said apparatus and the blocks are in working order. The blocks are preferably a mile in length, made up of sections of half a mile, the current always flowing through 60 the block in advance of the trains. The cab is the source of electrical energy.

Figure 1 is a diagrammatic view of my track divided into the blocks, showing east-bound and west-bound trains approaching each other 65 or stationary. Fig. 2 is a view similar to Fig. 1, the position of the east-bound train being changed. Fig. 3 is a diagrammatic view showing my blocks for the west-bound train.

In the drawings like characters of reference 70 indicate corresponding parts in each figure.

The track is divided into a series of blocks of any desired length. The first track-rail A is divided into a series of insulated sections, while the second track-rail D is not divided 75 into sections and is used as a common path for the return-current of the several blocks. Preferably (though not essentially) situated within the rails A and D is the first third rail E, which is divided into insulated sections, 80 preferably of the same length as the insulated sections of the first track-rail A. A single east-bound block consists of one of the sections E' of the first third rail, one of the immediately preceding sections A² of the first track-rail, 85 the wiring B connecting the section E' to the section A², the wiring C connecting the section A² with the second track-rail D, and the portion of the second track-rail D from the point where the wiring C connects therewith 90 back to the train.

A³ represents insulating-points for the sections of the first track-rail A, and E² represents insulating-points for the sections of the first third rail E. I preferably use a resistance-coil J in the wiring of each block, but 95 may dispense with same.

K is the east-bound train or engineer's cab, and K' the west-bound train or engineer's cab. These cabs are suitably provided with any 100 suitable conducting-shoes L and M and L' and M', respectively, which respectively operate on the first third rail E and second third rail E³. The said cabs are each provided with a source of electrical energy O', 105 an ordinary signal-magnet O, an electrical apparatus P, and an electromagnet Q, both operated by an excess of current flowing through the circuit, the feed-wire R and return-wire R' putting in circuit said sources of electrical 110

energy and devices in the cabs with their blocks through the said conducting-shoes, the current returning from said second track-rail D through the axle of the cabs back to sources of electrical energy. The second third rail E³ is divided into a series of insulated sections E⁴ of same length as the sections A², and by means of the line-wire E⁵ said insulated sections E⁴ are wired to the extreme end of the 10 immediately preceding insulated sections A². By means of the wiring C common to both blocks the current passes from said insulated sections A² into the second track-rail D and thence back to the cab K'. The block for the 15 cab K will be easily seen by following out the arrows without tails, Fig. 1, and the block of the cab K' will be seen by following out the arrows without tails in Fig. 3.

E⁶ represents the insulating-points for the 20 second third rail E³. The insulated sections E⁴, together with their corresponding length of second track-rail D adjacent thereto, constitute the home portion of the block for the train K, and the insulated sections A² of the 25 first track-rail A, together with their corresponding length of second track-rail D wired thereto, constitute the distant portion of the block for the said train. The insulated sections A², together with the line-wiring E⁵, 30 constitute the distant portion of the west-bound block for the train K', and the insulated sections E⁴, together with their corresponding length of second track-rail D adjacent thereto, constitute the home portion of 35 the west-bound block for the said train. In all cases the shoes M and M' enter the block first, and, as shown, the shoes L and L' preferably enter therein simultaneously with the cabs. If desired, the shoes L and L' may enter 40 the block before the train or locomotive.

As shown in Fig. 1, the locomotives K and K' are about a mile and a half apart. In case one of the sections A² should be broken—say at E⁷—the current from the cab K will naturally 45 follow the line-wire E⁵ in the direction indicated by arrows with tails, and by following out the arrows with crossed tails in Fig. 1 it will be seen that the current from the cab K' will flow through the line-wire E⁵ to meet 50 the current from the cab K. As these currents will be of the same kind and strength it will be understood that they will neutralize each other, thus through the ordinary signal-magnets O indicating to the engineers in both 55 cabs that there is an open circuit, and they will act accordingly.

Should the cabs be in the position indicated in Fig. 2, by following out the path of the current as shown by arrows it will be seen that 60 the circuit is short-circuited, thus putting the sources of electrical energy O' in series and causing either of the apparatus P and Q in both cabs to notify the engineers of the condition of their blocks.

65 From the above description of the opera-

tion it will be understood that the trains cannot approach each other nor can the circuits be open when the trains are a mile and a half or less distant from each other, or according to the length of the block-sections, without 70 the engineers being warned. Should either of the cabs be in such position that their live blocks do not overlap each other, it will be understood that the said blocks will operate independently, and the apparatus in the two 75 cabs will indicate the condition of same.

Referring to Fig. 3, I show the wiring for the west-bound block (shown in Figs. 1 and 2) applied to a single track, and the path of the circuit will be seen therefrom. Under all circumstances, with no defect in the tracks, the device O will be subject to normal current and will give a "safety" signal. With the rails broken or equivalent defect, O will act as a defect-magnet, while when the train K 85 short-circuits the adjacent block the apparatus P and Q from both trains are influenced by excessive current to give the proper indication.

If desired, I may use electropneumatic means 90 described in my before-mentioned application in connection with the herein-described invention.

I show the apparatus P and Q, but need not necessarily use both together. However, I 95 prefer to have the same on the same circuit, so that in case one should get out of order the other one will be sure to operate.

The shoes shown will of course be wide enough apart in actual practice to bridge all 100 dead-centers caused by crossed tracks or switch-centers, so that the train will always be in communication with its block. It will of course be understood that if there were no switches or track it would not be necessary for 105 me to use two shoes. I have not described nor shown any switches in connection with my blocks herein described, nor have I shown the stations wired thereto, because these points are not necessary in order to a complete understanding of my present invention, besides they have been fully described in my before-mentioned application.

In Figs. 1 and 2 I show a double set of shoes L², L³, L⁴, and L⁵, which operate, respectively, 115 on the second third rail E³ and the first third rail E. These shoes are for the purpose of putting the trains in communication with their blocks when they may happen to move backward. When the train is to move backward, the engineer will move the switch O² so as to direct current into the wiring O³, which leads to said shoes. When the train is moving forward, the switch O² occupies the position shown in Figs. 1 and 2. In case the train K' should move backward it will be understood that the current will flow through the east-bound block, 120 as fully shown in Fig. 1 in connection with the cab K, and should the cab K move backward the current will flow through the west- 125 130

bound block, as fully shown in Fig. 1 in connection with the cab K'.

The resistance of the circuits of the blocks must be equal, and I do not confine myself to any particular way of equalizing their resistance.

I do not confine myself to the construction herein shown and described, as same can be altered in many ways without departing from the spirit of my invention.

What I claim as my invention is—

1. In a system of the class described, the combination with the east-bound block comprising one insulated section of a conductor which is divided into a series of insulated sections; an insulated section, of the first track-rail which is divided into a series of insulated sections; a second track-rail used as a common conductor for all the blocks; suitable wiring for connecting said insulated section of the said conductor to the immediately preceding insulated section of said first track-rail, and suitable wiring for connecting the said immediately preceding section of said first track-rail to the said second track-rail, of a west-bound block comprising one insulated section of a second conductor which is divided into a series of insulated sections, and a line-wiring connecting one end of said insulated section of said second conductor to the extreme end of the immediately preceding insulated section of said second track-rail.

2. In a system of the class described, the combination with the east-bound block comprising one insulated section of a conductor which is divided into a series of insulated sections; an insulated section, of the first track-rail which is divided into a series of insulated sections; a second track-rail used as a common conductor for all the blocks; suitable wiring for connecting said insulated section of the said conductor to the immediately preceding insulated section of said first track-rail; suitable wiring for connecting the said immediately preceding section of said first track-rail to said second track-rail, and a resistance-coil in the wiring for said block, of a west-bound block comprising one insulated section of a second conductor which is divided into a series of insulated sections, and a line-wiring connecting one end of said insulated section of said second conductor to the extreme end of the immediately preceding insulated section of said second track-rail.

3. In a system of the class described, the combination with the east-bound block comprising one insulated section of a conductor which is divided into a series of insulated sections; an insulated section, of the first track-rail which is divided into a series of insulated sections; a second track-rail used as a common conductor for all the blocks; suitable wiring for connecting said insulated section of the said conductor to the immediately preceding insulated section of said first track-

70 rail; suitable wiring for connecting the immediately preceding section of said first track-rail to the said second track-rail; a source of electrical energy placed in the first cab; electrically-operated signaling means in said first cab in circuit therewith and with said block for the purpose of indicating to the engineer when the circuit is open, and means for completing the circuit between said block and source of electrical energy, of a west-bound 75 block comprising one insulated section of a second conductor which is divided into a series of insulated sections; line-wiring connecting one end of said insulated section of said second conductor to the extreme end of the 80 immediately preceding insulated section of said second track-rail; a source of electrical energy placed in the second cab; electrically-operated signaling means in said second cab and in circuit therewith and with said block 85 for the purpose of indicating to the engineer when the circuit is open, and means for completing the circuit between said block and said second source of electrical energy.

4. In a system of the class described, the 90 combination with the east-bound block comprising one insulated section of a conductor which is divided into a series of insulated sections; an insulated section, of the first track-rail which is divided into a series of insulated 95 sections; a second track-rail used as a common conductor for all the blocks; suitable wiring for connecting said insulated section of the said conductor to the immediately preceding insulated section of said first track-rail; suitable wiring for connecting the immediately preceding section of said first track-rail to the said second track-rail; a resistance-coil in the wiring for said block; a source of 100 electrical energy placed in the first cab; electrically-operated signaling means in said first cab in circuit therewith and with said block 105 for the purpose of indicating to the engineer when the circuit is open, and means for completing the circuit between said block and source of electrical energy, of a west-bound 110 block comprising one insulated section of a second conductor which is divided into a series of insulated sections; line-wiring connecting one end of said insulated section of 115 said second conductor to the extreme end of the immediately preceding insulated section of said second track-rail; a source of electrical energy placed in the second cab; electrically-operated signaling means in said second 120 cab and in circuit therewith and with said block for the purpose of indicating to the engineer when the circuit is open, and means for completing the circuit between said block and said second source of electrical energy.

5. In a system of the class described, the combination with the east-bound block comprising one insulated section of a conductor which is divided into a series of insulated sections; an insulated section, of the first track-

- rail which is divided into a series of insulated sections; a second track-rail used as a common conductor for all the blocks; suitable wiring for connecting said insulated section of the 5 said conductor to the immediately preceding insulated section of said first track-rail; suitable wiring for connecting the immediately preceding section of said first track-rail to the said second track-rail; a source of electrical 10 energy placed in the first cab; electrically-operated signaling means in said first cab in circuit therewith and with said block for the purpose of indicating to the engineer when the circuit has been short-circuited, and means for 15 completing the circuit between said block and said source of electrical energy, of a west-bound block comprising one insulated section of a second conductor which is divided into a 20 series of insulated sections; line-wiring connecting one end of said insulated section of said second conductor to the extreme end of the immediately preceding insulated section of said second track-rail; a source of electrical 25 energy placed in the second cab; electrically-operated signaling means in said second cab and in circuit therewith and with said block for the purpose of indicating to the engineer when the circuit has been short-circuited, and means for completing the circuit between said 30 block and said second source of electrical energy.

6. In a system of the class described, the combination with the east-bound block comprising one insulated section of a conductor 35 which is divided into a series of insulated sections; an insulated section, of the first track-rail which is divided into a series of insulated sections; a second track-rail used as a common conductor for all the blocks; suitable wiring 40 for connecting said insulated section of the said conductor to the immediately preceding insulated section of said first track-rail; suitable wiring for connecting the immediately preceding section of said first track-rail to the 45 said second track-rail; a resistance-coil in the wiring for said block; a source of electrical energy placed in the first cab; electrically-operated signaling means in said first cab in circuit therewith and with said block for the 50 purpose of indicating to the engineer when the circuit has been short-circuited, and means for completing the circuit between said block and said source of electrical energy, of a west-bound block comprising one insulated section 55 of a second conductor which is divided into a series of insulated sections; line-wiring connecting one end of said insulated section of said second conductor to the extreme end of the immediately preceding insulated section 60 of said second track-rail; a source of electrical energy placed in the second cab; electrically-operated signaling means in said second cab and in circuit therewith and with said block for the purpose of indicating to the engineer 65 when the circuit has been short-circuited, and

means for completing the circuit between said block and said second source of electrical energy.

7. In a system of the class described, the combination with the east-bound block comprising one insulated section of a conductor which is divided into a series of insulated sections; an insulated section, of the first track-rail which is divided into a series of insulated sections; a second track-rail used as a common conductor for all the blocks; suitable wiring for connecting said insulated section of the said conductor to the immediately preceding insulated section of said first track-rail; suitable wiring for connecting the immediately preceding section of said first track-rail to the said second track-rail; a source of electrical energy placed in the first cab; electrically-operated signaling means operated when the circuit is open; electrically-operated signaling means operated when the circuit has been short-circuited, both placed in said first cab, and on same circuit with said source of electrical energy, and means for completing the circuit between said block and said source of electrical energy, of a west-bound block comprising one insulated section of a second conductor which is divided into a series of insulated sections; line-wiring connecting one end of said insulated section of said second conductor to the extreme end of the immediately preceding insulated section of said second track-rail; a source of electrical energy placed in the second cab; electrically-operated sig- 70
75

in the second cab; electrically-operated signaling means operated when the circuit is open and electrically-operated signaling means operated when the circuit has been short-circuited, both placed in the said second cab and on same circuit with said source of electrical energy and with said block, and means for completing the circuit between said block and said second source of electrical energy.

8. In a system of the class described, the combination with the east-bound block comprising one insulated section of a conductor which is divided into a series of insulated sections; an insulated section, of the first track-rail which is divided into a series of insulated sections; a second track-rail used as a common conductor for all the blocks; suitable wiring for connecting said insulated section of the said conductor to the immediately preceding insulated section of said first track-rail; suitable wiring for connecting the immediately preceding section of said first track-rail to the said second track-rail; a resistance-coil in the wiring for said block; a source of electrical energy placed in the first cab; electrically-operated signaling means operated when the circuit is open, and electrically-operated signaling means operated when the circuit has been short-circuited, both placed in said first cab, and on same circuit with said source of electrical energy, and means for completing the circuit between said 130

block and said source of electrical energy, of a west-bound block comprising one insulated section of a second conductor which is divided into a series of insulated sections; line-wiring connecting one end of said insulated section of said second conductor to the extreme end of the immediately preceding insulated section of said second track-rail; a source of electrical energy placed in the second cab; electrically-operated signaling means operated when the circuit is open and electrically-operated signaling means operated when the circuit has been short-circuited, both placed in the said second cab and on same circuit with said source of electrical energy and with said block, and means for completing the circuit between said block and said second source of electrical energy.

9. In a system of the class described, a block comprising one insulated section of a conductor which is divided into a series of insulated sections; an insulated section, of the first track-rail which is divided into a series of insulated sections; a second track-rail used as a common conductor for all the blocks; line-wiring connecting one end of said section of said conductor with the extreme end of the immediately preceding insulated section of said first track-rail, and suitable wiring for connecting the other end of said immediately preceding insulated section of said first track-rail to the second track-rail.

10. In a system of the class described, a block comprising one insulated section of a conductor which is divided into a series of insulated sections; an insulated section, of the first track-rail which is divided into a series of insulated sections; a second track-rail used as a common conductor for all the blocks; line-wiring connecting one end of said section of said conductor with the extreme end of the immediately preceding insulated section of said first track-rail; suitable wiring for connecting the other end of said immediately preceding insulated section of said first track-rail to the second track-rail, and a resistance-coil in the wiring for said block.

11. In a system of the class described, the combination with a block comprising one insulated section of a conductor which is divided into a series of insulated sections; an insulated section of a first track-rail which is divided into a series of insulated sections; a second track-rail used as a common conductor for all the blocks; line-wiring connecting one end of said section of said conductor with the extreme end of the immediately preceding insulated section of said first track-rail, and suitable wiring for connecting the other end of said immediately preceding insulated section of said first track-rail to the second track-rail, of a source of electrical energy placed in the cab; electrically-operated signaling means in said cab in circuit therewith and with said block for the purpose of indicating to the en-

gineer when the circuit is open, and means for completing the circuit between said block and the said source of electrical energy.

12. In a system of the class described, the combination with a block comprising one insulated section of a conductor which is divided into a series of insulated sections; an insulated section, of a first track-rail which is divided into a series of insulated sections; a second track-rail used as a common conductor for all the blocks; line-wiring connecting one end of said section of said conductor with the extreme end of the immediately preceding insulated section of said first track-rail; suitable wiring for connecting the other end of said immediately preceding insulated section of said first track-rail to the second track-rail, and a resistance-coil in the wiring for said block, of a source of electrical energy placed in the cab; electrically-operated signaling means in said cab in circuit therewith and with said block for the purpose of indicating to the engineer when the circuit is open, and means for completing the circuit between said block and the said source of electrical energy.

13. In a system of the class described, the combination with a block comprising one insulated section of a conductor which is divided into a series of insulated sections; an insulated section of the first track-rail which is divided into a series of insulated sections; a second track-rail used as a common conductor for all the blocks; line-wiring connecting one end of said section of said conductor with the extreme end of the immediately preceding insulated section of said first track-rail, and suitable wiring for connecting the other end of said immediately preceding insulated section of said first track-rail to the second track-rail, of a source of electrical energy placed in the cab; electrically-operated signaling means operated when the circuit is open; electrically-operated signaling means operated when the circuit has been short-circuited, both placed in the cab and on same circuit with said source of electrical energy, and means for completing the circuit between said block and said source of electrical energy.

14. In a system of the class described, the combination with a block comprising one insulated section of a conductor which is divided into a series of insulated sections; an insulated section of the first track-rail which is divided into a series of insulated sections; a second track-rail used as a common conductor for all the blocks; line-wiring connecting one end of said section of said conductor with the extreme end of the immediately preceding insulated section of said first track-rail to the second track-rail; suitable wiring for connecting the other end of said immediately preceding insulated section of said first track-rail to the second track-rail, and a resistance-coil in the wiring for said block, of a source of electrical energy placed in the cab; electrically-operated

signaling means operated when the circuit is open; electrically-operated signaling means operated when the circuit has been short-circuited, both placed in the cab and on same circuit with said source of electrical energy, and means for completing the circuit between said block and said source of electrical energy.

In testimony whereof I have signed my name to this specification in the presence of two subscribing witnesses.

JOHN ALEXANDER WHYTE.
